UNITED STATES PATENT OFFICE.

JOHN K. FAGAN, OF WEST SUPERIOR, WISCONSIN.

ADJUSTABLE HINGE.

SPECIFICATION forming part of Letters Patent No. 532,044, dated January 8, 1895.

Application filed April 13, 1893. Serial No. 470,155. (No model.)

To all whom it may concern:

Be it known that I, JOHN K. FAGAN, of West Superior, Douglas county, Wisconsin, have invented certain Improvements in Adjustable Door-Hinges, of which the following is a specification.

My invention relates to improvements in door hinges, its object being to provide a hinge, the members of which are laterally adjustable for doors of different thickness, or to different positions of the same to compensate for the shrinkage of the door, and also to exert an elastic pressure upon the door to keep it tightly closed in its casing.

15 To this end my invention consists in forming one of the leaves of the hinge of three parts: first, a plate to be socketed in the casing; second, a plate connected to the hinge pintle and working in lateral slots in the first plate, the position of which is determined by screws passing through a lug upon the back of the first plate and threaded into a lug upon the second plate, a spring being interposed between the lugs, and third a face plate arranged 25 on top of the others and firmly secured by screws to the casing. By the forward movement of the screw passing through the lugs on the back of the plates, the pintle of the hinge is carried outward, the lugs being drawn together against the tension of the spring, but with the reverse movement of the screw the spring carries the pintle inward. By this means the position of the pintle may be adjusted to secure a perfect fit of the door in 35 the casing, the spring serving in addition to give an elastic pressure to the door.

My invention consists in the specific construction and combination hereinafter particularly described and claimed.

40 In the accompanying drawings forming part of this specification, Figure 1 is a plan view of the hinge, the outside plate being partly broken away to show the adjustable features of the inner and intermediate plates.

45 Fig. 2 is a central cross section of the same, and Fig. 3 is a section through the compound leaf or flap taken on line $x-x$ of Fig. 1.

In the drawings the hinge is shown made up of the flap 2, adapted to be secured to the 50 edge of the door and connected to the member A by means of the pintle 3 in the ordinary manner. The member A is made up of the flap 4 secured to the flap 2 by means of the pintle. This flap is provided with the transverse slots 5 and the central rearwardly 55 projecting screw threaded lug 6. 7 is a plate fitted to the socket in the casing and having end flanges 8, between which the flap 4 is fitted. It also is provided with hollow posts or bosses 9 which fit into the slots 5, and a rearwardly projecting lug 10 having an opening therethrough in alignment with the screw threaded opening in the lug 6, to receive the screw 11, the other end of which is fitted to the lug 6, as shown in Fig. 2. Interposed between the lugs 6 and 10, is the spiral spring 12 which serves to keep them separated to the limit permitted by the screw.

13 is a cap fitted over the flap 4 and plate 7, and secured in place by means of wood 70 screws passing through the holes 14. Other screws 15 are passed through openings in the plate 13 and through the hollow post 9, further securing the hinge in place. The plate 13 is secured to the plate 7 by means of the machine screws 16 passed through openings in the plate 13, and threaded into the plate 7, as shown in Fig. 3. The hinge is fitted to the door casing so that the head 17 of the screw 11 is exposed behind the hinge. When the screw is turned forward, the lug 6 is drawn toward the lug 10 against the tension of the spring 12, and the pintle is carried outward from the casing. With the reverse movement of the screw the tension of the spring 85 carries the lug 6 inward, and with it the pintle.

The hinge is adapted specially for use upon my improved beveled edge doors fitted to similarly beveled door casings. The position of the pintle of the hinge is adjusted by means 90 of the screw 11, so that the door when first hung will fit closely to the casing, the springs 12 yielding to allow the pintle of the hinge to be thrust outward as much as may be necessary to adapt the door to the casing. As the 95 door shrinks away, the springs will notwithstanding, tightly hold it close against the casing to the limit offered by the position of the screws 11. Upon further shrinkage of the door the screws 11 may be loosened to allow the springs to carry the door still farther inward. It will thus be seen that a consider-

able range of adjustment is possible to keep the door at all times fitted to its casing.

I claim—

1. In a hinge, the laterally expansible member in combination with spring restrained means for adjustably fixing the degree of expansion.
2. In a hinge, the compound flap comprising in combination the socket plate, the face plate, the slideable intermediate plate connected to the other member of the hinge the contracting spring, and the adjustable stop, substantially as described.
3. In a hinge, the expansible compound member, comprising in combination, the part to be socketed into the support, the part slid-

able thereon and connected to the other member of the hinge, the lugs upon said parts, the screw threaded into one of said lugs and turning freely in the other as a stop, the expansible spring interposed between said lugs, whereby the member tends to be contracted by the action of the spring, and the screw limits the contraction and adjusts the tension of the spring, substantially as described. 20 25

In testimony whereof I hereto set my hand his 6th day of March, 1893.

JOHN K. FAGAN.
